US00D664554S

(12) **United States Design Patent**
Nenoki

(10) **Patent No.:** **US D664,554 S**
(45) **Date of Patent:** **** Jul. 31, 2012**

(54) **DISPLAY SCREEN FOR X-RAY
MAMMOGRAPHY MACHINE WITH
GRAPHICAL USER INTERFACE**

(75) Inventor: **Yasuyo Nenoki**, Tokyo (JP)

(73) Assignee: **Fujifilm Corporation**, Tokyo (JP)

(**) Term: **14 Years**

(21) Appl. No.: **29/335,470**

(22) Filed: **Apr. 16, 2009**

(30) **Foreign Application Priority Data**

Oct. 16, 2008 (JP) 2008-026609

(51) **LOC (9) Cl.** **32-00**

(52) **U.S. Cl.** **D14/487**

(58) **Field of Classification Search** D14/485-495;
715/700-867

(57) **CLAIM**

The ornamental design for a display screen for x-ray mammography machine with graphical user interface, as shown and described.

DESCRIPTION

The single FIGURE is a front view of a display screen for x-ray mammography machine with graphical user interface showing my new design.

The outer rectangular broken line illustrates the display screen of the x-ray mammography machine and forms no part of the claimed design. The remaining broken lines illustrate portions of the graphical user interface that form no part of the claimed design.
